UNITED STATES PATENT OFFICE.

FRANZ PUENING, OF PITTSBURGH, PENNSYLVANIA, ASSIGNOR TO AMERICAN TAR PRODUCTS COMPANY, OF CHICAGO, ILLINOIS, A CORPORATION OF DELAWARE.

APPARATUS FOR COOKING LIQUEFIABLE BITUMINOUS MATERIALS.

Application filed December 20, 1920. Serial No. 421,853.

To all whom it may concern:

Be it known that I, FRANZ PUENING, a citizen of Germany, residing in Pittsburgh, in the county of Allegheny and State of Pennsylvania, have invented a new and useful Improvement in Apparatus for Coking Liquefiable Bituminous Materials, of which the following is a specification.

This invention comprehends improvements of general utility in the art of coking liquefiable bituminous materials, such as pitch; and also comprehends certain improvements especially applicable to pitch-coking apparatus of the general type exemplified in my prior Letters Patent of the United States for process and apparatus for coking pitch, No. 1,392,879, dated October 4, 1921.

The invention has for an object the provision of a thoroughly efficient means for sealing the top of the receptacle which contains the liquefiable bituminous material during the coking thereof, and yet in effecting such sealing through the instrumentality of a receptacle cover which is located between the roof of the furnace and the top of the receptacle, thereby preventing material which might leak out of the receptacle from spilling on the roof of the furnace and igniting, and also checking wasteful radiation of heat through the cover of the receptacle to the outer air. The reduction of the radiation factor to a minimum permits the coking to be carried on efficiently with the employment of lower temperatures than have heretofore been found practicable, for the reason that the temperature need not be raised to compensate for radiation losses and only such heat need be supplied to the interior of the receptacle as is necessary to coke the material. An important advantage accrues from the employment of lower temperatures inasmuch as such lower temperatures are less destructive to the receptacles and other parts with a consequent prolongation of their service. The sealing devices of the invention are effective in large measure to prevent leakage from the pot or receptacle. However, because of the novel arrangement of the receptacle cover with respect to the furnace roof, in the event leakages should occur, the spilled material will fall directly into the furnace, where it can do no damage. In the case of spilt pitch, the pitch will be simply converted into coke which may be

removed from the furnace as desired. Moreover, if suction be applied to the distillate outlet of the receptacle to assist the discharge of the distillate no air can enter the receptacle and cause an explosion. Although a small amount of burned fuel from the furnace may be drawn into the receptacle, no harm would result therefrom, but, on the contrary, the waste gas would help to convey the distillate out of the receptacle and thus assist the discharge of distillates.

Other objects of the invention are the provision of efficient mechanism for suspending the receptacle within the furnace, and a novel mechanism for clamping the cover on the receptacle with a yielding pressure, so as positively to force the cover into sealing engagement with all portions of the top of the receptacle.

In addition to the general objects recited above, the invention has for further objects such other improvements or advantages in construction and operation as are found to obtain in the structures and devices herein-after described or claimed.

In the accompanying drawings, forming a part of this specification, and showing, for purposes of exemplification, a preferred form and manner in which the invention may be embodied and practiced, but without limiting the claimed invention specifically to such illustrative instance or instances:

Fig. 1 is a vertical sectional elevation of an apparatus for coking liquefiable bituminous material constructed in accordance with the present improvements;

Fig. 2 is a horizontal sectional elevation of the same, taken in a plane indicated by the line 2—2 of Fig. 1;

Fig. 3 is a detailed vertical sectional elevation taken in a plane indicated by the line 3—3 of Fig. 1;

Fig. 4 is another detailed vertical sectional elevation taken in a plane indicated by the line 4—4 of Fig. 5; and

Fig. 5 is a view similar to Fig. 1 but illustrating another form of the invention.

The same characters of reference indicate the same parts in each of the several views of the drawings.

In the embodiment illustrated in the accompanying drawings, the invention is applied to a pitch-coking receptacle or pot of the general form and character exemplified in my co-pending application aforesaid.

For convenience, the present description will be confined to the present illustrated embodiment of the invention; the novel features and improvements made by the invention are, however, susceptible of other applications; hence, the scope of the invention is not confined to the specific use and specific embodiment herein described as an illustrative example.

10 Referring to the drawings, there is shown at 11 the side wall of a furnace chamber 12, within which is developed the heat necessary for coking the material contained within the pot or receptacle 13. The construction of 15 the furnace is immaterial to the present invention, and, for present purposes, the furnace wall 11 may be considered either as the wall of a stationary coking apparatus; or of a furnace construction in which a plurality 20 of receptacles are conveyed through the furnace chamber, the coking of the material charged into said receptacles being effected during their movement through the furnace chamber. At the top of the furnace walls 25 11 which are respectively located on opposite sides of the hereinafter described receptacles or pots, there are provided troughs 14, containing sand, designated at 15, into which sand dip the down-turned flanges 16 that 30 are respectively provided at the opposite sides of the furnace roof 17. The roof 17 may be constructed of metallic roof plates secured together in any suitable manner and is preferably covered with a layer of insulating material 18 to prevent excessive loss of heat by radiation from the furnace chamber, and thus to permit conduction of heat through the lower metallic shell 20 to the top portion of the receptacle 13, where the heat 35 conducted thereto is utilized for keeping the temperature high enough to prevent condensation of the distillates which gather in the upper portion of the receptacle. Escape of 40 gases from the furnace chamber 12 is prevented by the sand seals 15 which surround the submerged portions of the down-turned flanges 16 at the opposite sides of the furnace roof.

In accordance with the invention, the 50 upper end of the receptacle or pot 13 is provided with a peripheral sealing-flange 19 secured to said pot in any suitable manner and preferably made of relatively thicker metal than the main body portion of the receptacle, 55 not only to provide an exceedingly strong construction at the upper end of the receptacle, but also to slow up the heat penetration at this point in order to prevent the application of excessive temperatures to 60 the vapors and distillates in the top of the receptacle.

During the coking of the material within the receptacle 13, the upper open-mouthed end of the latter is closed by means of a receptacle cover 20. Said cover 20 is provided

, with a downwardly-projecting sealing flange 21 adapted for co-operative sealing engagement with the top sealing surface 22 of the sealing ring or flange 19 carried by the receptacle. The cover 20 is suspended from the roof 17 of the furnace by means of a plurality of bolts 23 which are respectively screwed into lugs 24 projecting from the top face of the cover. These bolts 23 are passed loosely through holes formed in a ring 25 mounted on top of the furnace roof 17, and the receptacle cover 20 is prevented from falling into the furnace chamber by nuts 26 applied to the upper ends of said bolts which project beyond the aforesaid plate 25. This construction however permits the cover 20 to bear by gravity on the sealing flange 19 of the receptacle and such gravitational movement of the cover 20 is supplemented by a like gravitational movement of the furnace roof 17, which is permitted by reason of the fact that the opposite sides of the latter are supported within loose sand seals 15. The result is that the entire weight of the cover 20 and the furnace roof 17 is supported by the sealing flange 19 of the receptacle, a condition tending to seal the cover 20 on the top of the receptacle and to provide a substantial leak-tight joint.

The invention, however, supplements the sealing effect produced by the above set forth gravitational movements of the furnace roof and receptacle cover, by the provision of means for positively forcing the receptacle cover, preferably with a yielding pressure, into sealing engagement with a top sealing flange of the receptacle. Formed at intervals along the peripheral portion of the cover 20 are sockets 27 into which project the lower ends respectively of pressure pins 28, there being, in the present instance, twelve of said pressure pins. The upper ends of said pressure pins 28 are respectively fulcrumed at 29 to pin-operating-levers 30, the fulcrum points 29 of said levers 30 being between their inner and outer ends as shown. These levers 30 are disposed radially of the receptacle cover 20 and their outer ends 31 are respectively adapted to be moved into or out of engagement with co-operating abutments 32 depending from a supporting ring 33. Mounted on the roof 17, substantially above the center of the cover 20, is a vertically-projecting supporting rod 34, on which is slidably mounted an encircling sleeve 35, the latter carrying at its lower end an upper disk 36 and a lower disk 37. The upper end of said sleeve 35 is pivoted at 38 to one member 39 of a toggle. This toggle member 39 is pivoted at 40 to the other toggle member 41 and the latter is in turn pivotally suspended at the point 42 on the cross bar 43 of the supporting frame. Extending outwardly from and formed with the upper toggle member 41 at a point below the pivot

40 is an operating handle 44. With this construction, by moving the handle 44 upwardly and toward the left, as viewed in Fig. 1, the central pivot point 40 will be shifted past dead center to a position such as indicated by dotted lines in Fig. 1. Such movement of the toggle members 39 and 41 is effective to draw up the sleeve 35 on the supporting rod 34 and with said sleeve the disks 36 and 37. On movement of the operating handle 44 in the reverse direction, a reverse movement of the toggle members 39 and 41 takes place with the result that the sleeve 35 and the disks 36 and 37 are lowered.

The upward and lowering movements of the disks 36 and 37 are utilized to relieve the cover 20 from clamping pressure exerted by the pressure pins 28 or to apply clamping pressure to said cover in the following manner: Secured between the disks 36 and 37 are vertical pins 45 on which the inner ends of the before-mentioned levers 30 are slidably mounted. Also encircling said pins 45 and bearing against the upper faces of the levers 30 are collars 46 which are pressed downwardly into engagement with the respective levers 30 by means of coil springs 47 interposed between the upper faces of said collars and the bottom face of the upper disk 36. On downward movement of the operating handle 44 the downward pressure exerted by the upper disk 36 is transmitted through the springs 47 and collars 46 to the inner ends of the several levers 30 and these levers move about their fulcrums 29 until their outer ends 31 engage the aforesaid abutments 32. After such engagement has been effected, the downward pressure exerted by the disk 36 is transmitted through the pins 28, causing the latter to press downwardly at points along the periphery of the receptacle cover 20 and press the sealing flange 21 thereof into positive sealing engagement with the sealing face 22 of the sealing flange 19 of the receptacle. The interposed springs 47 function as yielding connections interposed between the levers 30 and the means for applying pressure and serve to equalize the distribution of pressure to the several pressure pins 28, so as to insure sealing engagement at all points of the receptacle cover with the sealing flange of the receptacle. When it is desired to release the clamping pressure, above described, the operating handle 44 is moved in the opposite direction so that the bottom disk 37 is elevated. As the disk 37 moves upwardly it contacts with the bottom faces of the inner ends of the several levers 30 and in so doing lifts the lever 30 concurrently and the pressure pins 28, thereby releasing the receptacle from the clamping action of the cover.

65 The invention provides mechanism for

suspending the receptacle within the furnace chamber, independently of the receptacle cover 20 and the furnace roof 17 and of the hereinabove described means for applying clamping pressure to the receptacle cover 20. Secured to the seating flange 19 at spaced intervals therealong, is a plurality of, in the present instance, twelve, upwardly projecting hangers 48. These hangers are each provided at their upper ends with heads 49 adapted to be engaged respectively by the opposite clamping jaws 50 of the hooks 51. The hooks 51 correspond in number with the hangers 48 and are each rotatably mounted on horizontal axes constituted by U-bolts 52 supported by the ring 33 of the main supporting frame. A rotatable ring 53 is provided with a plurality of inwardly projecting pins 54 which are respectively passed through the hooks 51. With this construction the several hooks 51 may be disengaged in unison from the heads 49 of their operating hangers 48 by a rotary movement of the ring 53 in one direction or may be moved into locking engagement with the heads of said hangers by a rotary movement of said ring 53 in the opposite direction.

In order, however, to effect disengagement of the hooks 51 from the hangers 48, when, for example, it is desired to dump the coke 13 on the hooks 51 must be relieved. For this purpose, the supporting ring 33 and its supporting frame may be lowered by means of a bail 55 secured to the supporting frame, such lowering movement of the bail 55 being accompanied by a concurrent lowering movement of the ring 53 and the hooks 51, which are supported thereby. At this time the pot 13 will be suitably supported on its bottom, so that the hooks 51 may be moved clear of the weight of the pot, and readily disengaged by a rotary movement of the ring 53. If desired, the pressure between the hooks 51 and the hangers 48 of the pot may be relieved by slightly lifting the pot, instead of lowering the ring 33.

The pot or receptacle 13, is charged through a charging pipe 56 and the vapors of distillation which arise from the coking of the material within the receptacle pass out through a vapor outlet 57.

In the form of the invention illustrated in Fig. 5, the separate furnace roof and receptacle cover of the form hereinabove described is substituted by a combined furnace roof and receptacle cover 58 constructed of a bottom metallic section 59 and an upper insulating section 60. The metallic section 59 projects beyond the sides of the receptacle 13 and is thus directly exposed to the heat within the furnace chamber 12. Said metallic section 59 acts to conduct heat into the upper portion of the receptacle 13 and keep said portion of the receptacle at a tem-

perature high enough to prevent condensation of distillates. At the same time the insulating section 60 prevents excessive radiation to the outer air and consequent loss of heat.

5 The invention as hereinabove set forth is embodied in a particular form of invention but may be variously embodied within the scope of the claims hereinafter made.

I claim:

- 10 1. In an apparatus for coking liquefiable bituminous materials, in combination: a furnace chamber; a receptacle for containing the material to be coked; a plurality of suspension devices engageable with said receptacle for holding the latter suspended within said furnace chamber; means for releasing said suspension devices with respect to said receptacle; a furnace roof mounted above the upper end of said receptacle; a receptacle cover interposed between said roof and the upper end of said receptacle; both said roof and said receptacle cover bearing by gravity on the top of the receptacle; and means, operable independently of said suspension devices and of the gravitational movements of said roof and receptacle cover, for positively forcing the receptacle cover into sealing engagement with the top of said receptacle; substantially as specified.
- 15 2. In an apparatus for coking liquefiable bituminous materials, in combination: a furnace chamber; a receptacle for containing the material to be coked; a furnace roof mounted above the upper end of said receptacle; a receptacle cover interposed between said roof and the upper end of said receptacle; both said roof and said receptacle cover bearing by gravity on the top of the receptacle; and a plurality of suspension devices engageable with said receptacle, independently of the furnace roof and the receptacle cover, for holding said receptacle suspended within said furnace chamber; substantially as specified.
- 20 3. In an apparatus for coking liquefiable bituminous materials, in combination: a furnace chamber; a receptacle for containing the material to be coked; a furnace roof mounted above the upper end of said receptacle; a receptacle cover interposed between said roof and the upper end of said receptacle; both said roof and said receptacle cover bearing by gravity on the top of the receptacle; and a plurality of suspension devices engageable with said receptacle, for positively forcing the receptacle cover into sealing engagement with the top of said receptacle, substantially as specified.
- 25 4. In an apparatus for coking liquefiable bituminous materials, in combination: a furnace chamber; a receptacle for containing the material to be coked; a furnace roof mounted above the upper end of said receptacle; a receptacle cover interposed between said roof and the upper end of said receptacle; both said roof and said receptacle cover bearing by gravity on the top of the receptacle; and means, operable independently of the gravitational movements of said roof and said receptacle cover, for positively forcing the receptacle cover with a yielding pressure into sealing engagement with the top of said receptacle, substantially as specified.
- 30 5. In an apparatus for coking liquefiable bituminous materials, in combination with a furnace chamber: a receptacle for containing the material to be coked and adapted to be mounted within said furnace chamber; a furnace roof mounted above the upper end of said receptacle; a receptacle cover interposed between said roof and the upper end of said receptacle; both said roof and said receptacle cover bearing by gravity on the top of the receptacle; and means, operable independently of the gravitational movements of said roof and said receptacle cover, for positively forcing the receptacle cover with a yielding pressure into sealing engagement with the top of said receptacle, substantially as specified.
- 35 6. In an apparatus for coking liquefiable bituminous materials, in combination with a furnace chamber: a receptacle for containing the material to be coked mounted and adapted to be within said furnace chamber; a furnace roof mounted above the upper end of said receptacle; and a receptacle cover interposed between said roof and the upper end of said receptacle; both said roof and said receptacle cover bearing by gravity on the top of the receptacle, said roof being downwardly movable relative to the walls of said chamber; substantially as specified.
- 40 7. In an apparatus for coking liquefiable bituminous materials, in combination with a furnace chamber: a receptacle for containing the material to be coked and adapted to be mounted within said furnace chamber; a furnace roof mounted above the upper end of said receptacle; a receptacle cover interposed between said roof and the upper end of said receptacle; and means for positively forcing the receptacle cover into sealing engagement with the top of said receptacle; substantially as specified.
- 45 8. In an apparatus for coking liquefiable bituminous materials, in combination with a furnace chamber: a receptacle for containing the material to be coked and adapted to be mounted within said furnace chamber; a furnace roof mounted above the upper end of said receptacle; a receptacle cover interposed between said roof and the upper end of said receptacle; and means, operable with a yielding pressure, for positively forcing the receptacle cover into sealing engagement with the top of said receptacle.
- 50 9. In an apparatus for coking liquefiable bituminous materials, in combination: a furnace chamber; a receptacle for containing the material to be coked; a furnace roof mounted above the upper end of said receptacle; a receptacle cover interposed between said roof and the upper end of said receptacle; both said roof and said receptacle cover bearing by gravity on the top of the receptacle; a plurality of suspension devices engageable with said receptacle, independently of the furnace roof and the receptacle cover, for holding said receptacle suspended within said furnace chamber; substantially as specified.
- 55 10. In an apparatus for coking liquefiable bituminous materials, in combination: a furnace chamber; a receptacle for containing the material to be coked; a furnace roof mounted above the upper end of said receptacle; a receptacle cover interposed between said roof and the upper end of said receptacle; and means for releasing said suspension devices in unison with respect to said receptacle; substantially as specified.
- 60 11. In an apparatus for coking liquefiable bituminous materials, in combination: a furnace chamber; a receptacle for containing the material to be coked mounted within

with the top of said receptacle, substantially as specified.

9. In an apparatus for coking liquefiable bituminous materials, in combination: a receptacle for containing the material to be coked; a receptacle cover for closing the upper end of said receptacle and movable by gravity into said closing position; a furnace chamber containing said receptacle; and means forcing the cover into sealing engagement with the top of said receptacle, said means also closing the top of said furnace chamber; substantially as specified.

10. In an apparatus for coking liquefiable bituminous materials, in combination: a receptacle for containing the material to be coked; a receptacle cover for closing the upper end of said receptacle and movable by gravity in such closing position, and means, operable independently of the gravitational movement of said receptacle cover, for positively forcing the latter with a yielding pressure into sealing engagement with the top of said receptacle, substantially as specified.

11. In an apparatus for coking liquefiable bituminous materials, in combination: an open-mouthed receptacle for containing material to be coked; a receptacle cover engageable with the peripheral portion of said receptacle for closing the latter and movable by gravity into said closing position; a plurality of pressure devices disposed peripherally of said receptacle cover for positively forcing the latter into sealing engagement with the peripheral portion of said receptacle; means for applying pressure concurrently to each of said devices; and means for equalizing the pressure applied to said devices; substantially as specified.

12. In an apparatus for coking liquefiable bituminous materials, in combination: an open-mouthed receptacle for containing the material to be coked; a receptacle cover engageable with the peripheral portion of said receptacle for closing the latter and movable by gravity into said closing position; a plurality of pressure-transmitting pins engageable with the peripheral portion of said receptacle cover; levers individually cooperable with said pressure pins; a unitary lever-operating means for moving said levers concurrently to apply pressure to each of said pins, and yielding connections interposed between said levers and said lever-operating means; substantially as specified.

13. In an apparatus for coking liquefiable bituminous materials, in combination: a furnace chamber; a receptacle for containing the material to be coked and adapted to be mounted within said furnace chamber; a combined furnace roof and receptacle cover mounted above the upper end of said receptacle and extended beyond the sides of the latter; and means for positively forcing said combined furnace roof and receptacle cover into sealing engagement with the top of said receptacle, substantially as specified.

14. In an apparatus for coking pitch and the like, in combination: a furnace chamber, a receptacle for the pitch within said chamber, and a receptacle cover and furnace roof on the upper end of said receptacle, said roof having a movable seal with the furnace walls to retain gases and permit the receptacle-closing action of said cover and roof.

FRANZ PUENING.
